UNITED STATES PATENT OFFICE.

WILLIAM H. HALL, OF CICERO, ILLINOIS.

SUCTION DEVICE.

1,072,943.

Specification of Letters Patent.

Patented Sept. 9, 1913.

Application filed August 15, 1912. Serial No. 715,144.

To all whom it may concern:

Be it known that I, WILLIAM H. HALL, a citizen of the United States, residing at Cicero, in the county of Cook and State of Illinois, have invented certain new and useful Improvements in Suction Devices, of which the following is a specification.

This invention relates in general to suction devices, and more particularly to cleaners for cleaning rugs, carpets, etc., when on the floor, and one of the primary objects of the invention is the provision of a cleaner of this general character comprising a suction cleaning device for removing fine dirt, dust, etc., from the floor, and a revolving brush adapted to collect thread, lint and other objects which are not readily picked up by the suction device.

A further object is the provision of a novel and improved suction device which is separably mounted on the main frame of the machine and may be swung back to permit the removal of the suction dust-pan, the brush and its collecting pan, and may be swung down over the top of the frame to form a cover for the machine and effect a hermetic connection between the suction nozzle and the suction device.

Other objects and advantages of the present invention will be readily understood by those skilled in the art as the invention becomes better understood by reference to the following description when considered in connection with the accompanying drawings.

Referring to the drawings:—Figure 1 is a perspective view of a cleaner embodying my invention showing the suction device separated from the main frame of the machine and tilted partway back; Fig. 2 is an enlarged fragmentary elevation showing the suction device tilted back to its extreme position; Fig. 3 is a rear view of the machine, part of the casing being broken away to show the interior thereof; Fig. 4 is a sectional view taken substantially on the line 4—4 of Fig. 3; Fig. 5 is a perspective view of the brush pan, and Fig. 6 is a fragmentary sectional view through one of the rear corners of the machine.

Referring to the drawings, 6 designates generally the main frame of the machine constructed to provide an open-top air chamber 7, and a nozzle 8 at the front of the machine having a channel or passageway 9 communicating with the air chamber 7. A

dust-pan 11, preferably constructed of tin or light sheet metal, is adapted to set loosely in the air chamber 7 and to receive the dust and dirt drawn in through the nozzle passageway 9. A screen comprising a frame 12 and a suitable fabric 13 stretched thereon is adapted to be positioned in the main frame 6 directly over the pan, as shown in Fig. 4, the air chamber 7 being provided adjacent its open top with a peripheral ledge or shoulder 14 upon which the screen rests. Upon the upper edge of the screen frame there is provided a gasket 15 of leather or other suitable material which projects from the perimeter of the screen and overlies the upper edges of the dust chamber walls, the gasket being adapted to afford a hermetic connection between the air chamber and the air pump in a manner which will be later described.

Each rear side wall of the frame 6 has a bracket 16 secured thereto, said bracket being bent inwardly at the end of the frame and then rearwardly as shown in Fig. 6, so as to project beyond the frame in position to receive a transversely extending shaft 17 upon the ends of which are mounted the driving wheels 18, by means of which the rear end of the machine is supported. The front of the machine rests upon the nozzle 8, and the machine is caused to travel back and forth upon the floor or other surface being cleaned by a suitable handle 19 connected with a bail 21 pivotally attached to each side of the main frame.

Suction is induced through the nozzle 8 by means of a suitable suction device or air pump, one practical form of which is shown in Figs. 1, 3 and 4. This pump comprises a flat base 22 provided at its rear end with downwardly projecting brackets 23 supported on the shaft 17 adjacent the brackets 16. The pump base therefore has a hinged connection with the main frame of the machine which permits the pump to be closed down over the frame in the position shown in Fig. 4, thereby forming a cover therefor. A suitable gasket 24 is preferably provided on the lower face of the base member to cooperate with the gasket 15 on the screen frame to effect a hermetic connection between the pump base and the air chamber 7. Upon the base 22 is mounted a pair of compound bellows designated generally by reference characters 25. Each of these bellows consists of a stationary bottom mem-

ber or plate 26 secured to the base member 22, a stationary top member or plate 27 rigidly attached to the member 26 at the nose of the bellows by a block 28, and a movable intermediate member 29. The rear ends of the members 27 are supported in elevated position by straps or braces 31 fixedly secured at their lower ends to the members 26 and at their upper ends to the members 27. The intermediate member 29 is hinged to the block 28 preferably by a 2-ply leather strap or sheet 32 which extends throughout the width of the bellows, and has its projecting ends 33 and 34 secured to the sides of the members 27 and 26 respectively to insure an air-tight partition between the two air chambers of each bellows. The sides and rear end of the member 29 are connected with the members 26 and 27 by any suitable flexible material 35 adapted to collapse and permit up and down movement of the member 29 between the members 26 and 27. The rear end of each member 29 is connected with its respective driving wheel 18 by a pivoted link 36, which upon rotation of the wheel swings the member 29 up and down about the leather hinges 32.

The lower chamber of each bellows communicates with the air chamber 7 in the main frame through an aperture 30 over which is positioned a valve consisting of a pair of metal disks 37 embracing a flexible disk 38 of leather or other suitable material. A spring 39 affixed to the member 26 by screws 41 or other suitable fastening means projects over the valve and is provided near its end with an aperture which fits loosely over a stud 42 projecting from the upper face of the valve. The valve is thereby yielding held in operative position, and may be removed when occasion requires by simply lifting the free end of the spring 39 out of engagement with the stud 42, whereupon the valve may be readily removed. The exhaust valves 43 for the lower chambers are substantially similar to the inlet valve, and cover the exhaust openings 44 in the base of the bellows. Near the nose of the bellows the members 26 and 29 are provided with aligned openings 45 and 46 which are connected by a collapsible tube 47 through which communication is established between the air chamber 7 and the upper chamber of the bellows. The tube 47 may be constructed of any suitable material, and is affixed at its ends to the members 26 and 29 in any approved manner. An inlet valve 47' and an outlet valve 48 permit ingress and egress of air to and from the upper chamber, these valves being preferably of similar construction to the inlet valve for the lower chamber. A casing 50 of sheet metal or other suitable material is disposed over the bellows and fixedly attached to the bellows base 22, this casing being adapted

to afford protection to the bellows and give the machine a neat and rounded appearance.

From the foregoing it will be understood that when the machine is run back and forth across a floor or carpet the dust will be drawn into the air chamber through the nozzle passageway 9, where it will be screened from the air by the screen 13 and deposited in the removable dust-pan 11, the pair of compound bellows being adapted to maintain a practically continuous suction action through the nozzle.

Certain pieces of solid material, such as lint, pieces of string, etc., which cling to the carpet are not readily taken up by the suction device and therefore I have provided a mechanical cleaner in the form of a brush which is adapted to pick up and collect material of this character. The brush designated by 49 may be of any preferred construction, and has pintles 51 projecting from the ends thereof and adapted to revolve in suitable slotted bearings formed in the brackets 16. In some instances it may not be desirable to use the brush, and in order that it may be readily removed when not required, or for the purposes of cleaning, the slots 52 formed in the bracket 16 are open at their upper ends to receive the pintles 51, and are provided at their lower ends with an offset portion 53 in which the pintles are disposed when the brush is in operative position. In order to yieldingly hold the brush in position I prefer to recess the side members of the frame as indicated at 54 and to dispose a suitable leaf spring 55 in each recess which normally and yieldingly retains the pintles in the position shown in Fig. 4. It will be obvious that by simply moving the brush to the left, viewing Fig. 4, against the force of the springs it may be readily lifted out of the slots and removed from the machine.

A collecting pan 56, shown in Fig. 5, is made preferably of sheet metal and formed to removably fit down over the brush and provide collecting pockets 57 and 58 at each side of the brush in which the material taken up by the brush is deposited. It will be observed that the construction of the machine frame affords sufficient space on each side of the brush to accommodate a dirt-receiving pocket, thereby providing a repository for the reception of the material collected by the brush irrespective of the direction of travel of the brush. This pan is equipped with projecting portions 59 at the ends adapted to rest upon the main frame of the machine and support the pan in operative position. When the bellows are turned back into inoperative position, as shown in Fig. 2, the pan 56 may be readily lifted out and dumped. An opening 61 is provided in the top of the pan to facilitate dumping, and in practice when it is desired to clean the ma-

chine the screen 13 is usually lifted out and the pan 56 dumped into the pan 11, whereupon all of the refuse may be disposed of by simply removing the pan 11 and dumping it.

The brush 49 is caused to operate when the apparatus is moved over the surface being cleaned by frictional engagement between the brush and one or both of the driving wheels 18. To this end an enlargement 60 is formed in the present embodiment upon the central shaft 60', which is engaged by a wheel 18 as shown in Fig. 6. Both the wheel and enlargement or either of them 15 may be provided with a cover of friction-producing material as rubber or the like to insure continuous operation of the brush portion 53. The slot 52 is preferably offset sufficiently to permit the spring 55 to hold the 20 enlargement 60 or the shaft 60' when no enlargement is provided in yielding engagement with the wheel 18.

In order to strengthen the brackets 16 and also to reinforce the rear wall of the 25 pan 56 I provide a cross-rod 62 secured at each end to a bracket 16 and extending transversely of the machine adjacent the rear wall of the pan 56. The brackets 16 are also equipped with suitable stops 63 to 30 limit the swinging movement of the bellows and support the bellows when in inoperative position, as shown in Fig. 2. The bellows may be clamped down to effect an air-tight connection with the air-chamber 7 by 35 any suitable fastening means. In the present instance, however, I have shown one practical fastening in the form of a member 64 pivoted to the front of the main frame and provided with a laterally opening slot adapted to coöperate with a pin 65 on a pivotal member 66 mounted in co-operative relation on the front of the bellows.

From the foregoing it will be understood that the device may be used either simply as a vacuum cleaner or as a combined vacuum and mechanical cleaner. When it is desired to clean the machine the bellows are tipped back into vertical 50 position, whereupon the screen 12 may be lifted out and brushed off, the pan 56 may be lifted out and dumped, the brush 49 may be removed and cleaned and the pan 11 may also be removed and dumped. The 55 various parts are all readily accessible when the bellows are tilted back, and then may be quickly and easily assembled by an inexperienced person. A single fastening means which clamps the bellows to the

frame serves to hold all of the parts in 60 operative position, and the unfastening of this means permits the bellows to be turned back so as to uncover all of the removable parts of the machine.

It is believed that my invention will be 65 understood from the foregoing without further description, and while I have shown and described a preferred embodiment thereof it will be apparent that various deviations from the structural details disclosed may be made without departing from the spirit of the invention as defined in the following claims.

I claim:

1. In a vacuum cleaner, the combination 75 of a suitable frame work forming the side walls and bottom of an air chamber and provided with an air inlet, a shaft at one end of said frame work, supporting wheels mounted thereon, and a pump hinged on 80 said shaft and adapted to close down over said chamber to form an air-tight connection with the walls thereof.
2. In a vacuum cleaner, the combination 85 of a suitable frame forming the side walls and bottom of an air chamber, a shaft carried by said frame, a pump swingingly mounted on said shaft to close down over said air chamber, driving connections between said shaft and pump, and means for 90 maintaining an air-tight connection between the pump base and said air chamber walls.
3. In a vacuum cleaner, the combination 95 of a body formed to provide an open top receptacle, a driving shaft mounted thereon, and a suction device mounted to swing about said shaft and having a base to fit the top of said receptacle, said body and base being adapted when closed upon each 100 other to provide an air chamber beneath the suction device.
4. In a vacuum cleaner, the combination 105 of a frame formed to provide an open top receptacle, a bellows having a base adapted to fit the top of said receptacle, a shaft carried by one end of the receptacle at the movable end of the bellows, means pivotally connecting the movable end of the bellows with said shaft, and driving connections 110 between said shaft and the movable portion of the bellows whereby said bellows may be swung back about the shaft without disconnecting the driving connections.

WILLIAM H. HALL.
